ELECTROLYTIC CELL

Charles Edward Bowen, Sandycroft, Chester, England, assignor to International Electrolytic Plant Company Limited, Sandycroft, Chester, England

Application November 19, 1946, Serial No. 710,789
In Great Britain November 24, 1945

10 Claims. (Cl. 204—256)

1

This invention relates to improvements in electrolytic cells and more particularly to electrolytic cells for the production of oxygen and hydrogen by the electrolysis of water of the type in which a number of cell frames are assembled together to form a unitary structure.

In such cells the gases passing out of the cells take with them entrained electrolyte which is subsequently separated from the gases in external separating means and returned to the cells.

One of the objects of the invention is to provide an improved construction of cell which allows the electrolyte to be efficiently separated from the gases immediately on their evolution so that external separating means are unnecessary. Other objects are to permit free circulation of the electrolyte without imposing strain on the diaphragms by localised pressures, and to obtain effective balancing between adjacent cells.

According to the invention an electrolytic cell is built up from a number of parallel skeleton frames, the members of each frame being of I or equivalent cross-section so that when the frames are assembled together compartments surrounding the cells proper are formed between the webs and flanges of the frames.

Each frame may be cast as a unit in metal or moulded from a suitable plastic material or it may be built up from members of the required cross-section.

An inwardly extending lip or ledge is conveniently formed integral with or secured to the inner flange of the frame to carry the diaphragm, and in cells for the production of oxygen and hydrogen this lip or ledge and the web of the frame section are offset to provide a greater space on the catholyte side of the diaphragm than on the anolyte side. The reason for this is that the hydrogen is evolved at twice the rate of the oxygen and entrains more than twice as much electrolyte, and the allocation of greater space for the catholyte eliminates local areas of high pressure on the diaphragm.

The joints between adjacent frames are of the full depth or width of the frame members so that there is a separate compartment extending all round the frame on each side of the web thereof, the compartment being defined by the web and flanges of the frame and the jointing.

Partitions are arranged at the junctions of the vertical side sections of the compartment with the bottom to isolate the bottom section from the rest.

Electrolyte is fed into the cell from the bottom section of each compartment through openings

5 in the upper flanges of the bottom frame member, and similar openings are provided in the bottom flange of the upper frame member through which gases from the chambers on opposite sides of the diaphragm together with any entrained electrolyte pass freely upwards into the top sections of the compartments on opposite sides of the web of the frame member. In these top sections the gas and electrolyte separate and the electrolyte flows along into the side sections while the gases on opposite sides of the web pass into separate outlets mounted on top of the frame and communicating by way of inclined passages in the frame members with the respective top sections.

10 One practical construction of cell in accordance with the invention for the electrolytic production of oxygen and hydrogen is illustrated by way of example in the accompanying drawings in which—

Figure 1 is an end elevation of one cell frame.

Figure 2 is a plan of the frame.

Figure 3 is a side elevation in part section on a larger scale of a frame.

15 Figure 4 is a similar elevation in part section of a frame from the other side.

Figure 5 is a side elevation in part section of three frames assembled together.

20 Each frame of the cell unit illustrated is of I or H cross-section with a web 10 and flanges 11, 12. The frame may be cast as a unit in metal or moulded from a suitable plastic material, or it may be built up from members of the required cross-section. The web 10 is offset from the central plane of the frame. On the inner flange of the frame there is an inwardly extending lip or ledge 13 which may be integral with or may be secured to the flange and which carries the diaphragm 14, this lip being offset to the same extent as the web 10.

25 When a number of frames are assembled together as shown in Figure 5 with the electrode plates 15 and a wide strip of jointing material 16 lying between the frames and of the full width of the frame members over the flanges there are formed on opposite sides of the web of each frame separate compartments 17, 18 extending completely around the cell.

30 Each of these compartments is defined by the web and flanges of the frame member and the jointing 16 which constitutes a partition between the adjacent compartments of adjacent frames.

35 The bottom section 19 of each compartment is isolated from the side sections by horizontal partitions 20.

Electrolyte is fed into the bottom section 19 of each compartment and flows upwardly into the cell through openings 21 in the upper flanges 11 of the bottom frame member. Gases generated in the cell on opposite sides of the diaphragm, together with any entrained electrolyte, pass upwardly through openings 22 in the lower flanges of the top frame member into the separate sections 17, 18 on opposite sides of the web. In these sections the gas and electrolyte separate and the electrolyte flows along into the side sections of the compartments. Gas from the section 17 on one side of the web flows through an inclined passage 23 in the upper flange of the frame member into an outlet 24 on the top of the frame while gas from the other section 18 flows through an oppositely inclined passage 25 to an outlet 26.

To allow movement of electrolyte between adjacent compartments openings 27 are provided in the web of the bottom frame member and small ports 28 are provided in the web separating the side sections adjacent to the partitions 29. Mixing of the gases is prevented by an externally made seal which maintains a certain minimum depth of electrolyte in the side sections of the compartments.

For the feeding of the electrolyte a pad or gasket 30 is provided at the bottom of the frame on each side to receive a block 31 of insulating material which is bored horizontally to form two vertically spaced ducts 32, 33 having their axes at right angles to the plane of the frame. The upper duct 32 is in communication through a horizontal passage 34 with the side section of the adjacent compartment above the partition 29 and the lower duct 33 is in communication through a passage 35 with the bottom section 19.

When a number of frames are assembled together as shown in Figure 5 packing washers 36 are arranged between the adjacent ends of the ducts in adjacent blocks which provide two continuous ducts extending along each side of the unit, the upper duct receiving the overflow electrolyte from the side sections of the compartments and the lower duct taking the return flow of electrolyte to the cells.

The overflow electrolyte can be taken off at any convenient point through a vessel having means for correcting the temperature of the electrolyte which is fed back to the cells either direct or through a circulating pump.

With a direct feed the side sections of the compartments are flooded with electrolyte and the circulation is caused by the difference in specific gravity between the electrolyte in the side sections of the compartments and the mixture of gas and electrolyte in the cell and also by the slight difference in temperature.

If a circulating pump is used the amount of electrolyte in the side sections of the compartments can be reduced by transference of the electrolyte to a balance tank and the rate of circulation of the electrolyte through the cells can be greatly increased, thus permitting an increased current rating. As the reduction of the amount of overflow leaves more space available the efficiency of the separation of the electrolyte from the gases is maintained at the higher rating.

The improved cell has a number of advantages in practice over existing cells amongst which are that efficient separation of the electrolyte from the gases is effected as soon as the gases are evolved, that effective balancing between the cells

is obtained, and that uniformity of electrolyte outflow from each cell is obtained by the control of the liquid level in the side sections of the compartments which prevents any disturbance of working conditions through current variations.

The duplication of the electrolyte circulating system largely eliminates inequalities in electrolyte concentration in individual cells, and the arrangement for handling the electrolyte circulation in insulated ducts of relatively small cross-section minimises stray current losses.

I claim:

1. An electrolytic cell comprising a plurality of skeleton frames assembled together in parallel relationship to form a unitary structure, each member of each of said frames being of I-section formed by spaced flanges and a connecting web, the webs of all the members in each frame being in the same plane, jointing material between the members of adjacent frames co-operating with the edges of the flanges and constituting partitions so as to form with the web and flanges of each frame closed compartments having top, side and bottom sections surrounding a cell space, and other partitions between the bottom section and the side sections of each of said compartments, each frame being provided with ports of communication between the top and bottom sections of said compartments and said cell space, with discharge ports from the top sections and from the lower parts of the side sections of said compartments, and with at least one inlet port to the bottom sections of said compartments.

2. An electrolytic cell as claimed in claim 1, wherein said jointing material is in sheet form.

3. An electrolytic cell as claimed in claim 1, each of said members including a lip extending inwardly from the inner flange thereof, and a diaphragm carried by the lips of the members of each frame.

4. An electrolytic cell as claimed in claim 1, each of said members including a lip extending inwardly from the inner flange thereof, said web and said lip being offset from the central plane of the frame, and a diaphragm carried by the lips of the members of each frame, whereby the compartment on the one side of the web of each frame is of greater volume than that on the other side and the cell space on the corresponding side of the diaphragm is of greater volume than that on the other side.

5. An electrolytic cell comprising a plurality of skeleton frames assembled together in parallel relationship to form a unitary structure, each member of each of said frames being of I-section formed by spaced flanges and a connecting web, the webs of all the members in each frame being in the same plane, jointing material between the members of adjacent frames co-operating with the edges of the flanges and constituting partitions so as to form with the web and flanges of each frame closed compartments surrounding a cell space, other partitions at the junction of the side sections of each compartment with the bottom section to isolate the bottom section, each frame being provided with openings in the upper flanges of the bottom frame member through which electrolyte passes from the bottom section into the cell space, means for withdrawing electrolyte from the side sections, and means for introducing electrolyte to the bottom sections.

6. An electrolytic cell as claimed in claim 5 wherein each frame is further provided with ports in the web of the frame member sep-

arating the side sections of adjacent compartments, said ports being above and close to the partitions at the junctions of the side sections with the bottom sections.

7. An electrolytic cell comprising a plurality of skeleton frames assembled together in parallel relationship to form a unitary structure, each member of each of said frames being of I-section formed by spaced flanges and a connecting web, the webs of all the members in each frame being in the same plane, jointing material between the members of adjacent frames and constituting partitions so as to form with the web and flanges of each frame closed compartments having top, side and bottom sections surrounding a cell space, a diaphragm secured to each frame in said cell space substantially in the plane of said webs, and other partitions between the bottom section and the side sections of each compartment, each frame being provided with first ports in the inner flange of its top member on opposite sides of the web to allow gases from the cell spaces on opposite sides of the diaphragm together with any entrained electrolyte to pass into the upper sections of the compartments on opposite sides of the web, second ports in the outer flange of the top member through which the gases may be taken off while electrolyte separated from the gases drains down into the side sections of the compartments, means for draining off electrolyte, and means for feeding electrolyte into the bottom sections.

8. An electrolytic cell comprising a plurality of skeleton frames assembled together in parallel relationship to form a unitary structure, each member of each of said frames being of I-section formed by spaced flanges and a connecting web, the webs of all the members in each frame being in the same plane, jointing material between the members of adjacent frames cooperating with the edges of the flanges and constituting partitions so as to form with the web and flanges of each frame closed compartments surrounding a cell space, other partitions at the junction of the side sections of each compartment with the bottom section to isolate the bottom section, each frame being provided with openings in the upper flanges of the bottom frame member through which electrolyte passes from the bottom sections into the cell space, a

gasket at the bottom of each frame on each side, a block of insulating material secured to each gasket, each block being provided with two vertically spaced horizontal ducts having their axes at right angles to the frame, said gaskets and the adjacent side members being provided with passages establishing communication between the upper ducts of the associated blocks and the side sections of the adjacent compartments and between the lower ducts and the bottom sections, said blocks, combining in said unitary structure of frames to provide two combined ducts extending along said structure on each side, the upper combined duct receiving the overflow electrolyte from the side sections, and the lower combined duct taking the return flow of electrolyte to the cells.

9. A frame of an electrolytic cell unit comprising a rectangular structure formed of top, side and bottom members, each of said members being of I-section formed by spaced inner and outer flanges and a connecting web, the webs of all the members being in the same plane, partitions across the flanges of the side members substantially at their junction with the bottom member so as to form on each side of said plane one bottom channel closed at its ends, and another continuous channel extending along the remaining sides of said rectangle, and each member having on its inner flange an inwardly extending lip for carrying a diaphragm.

10. A frame as claimed in claim 9, said webs and said lips being offset to one side of the central plane of the frame.
